UNITED STATES PATENT OFFICE.

CORNELIS ZULVER, OF LONDON, ENGLAND, ASSIGNOR OF ONE-HALF TO LAUNCELOT EUSTACE SMITH, OF SOUTH SHIELDS, ENGLAND.

FURNACE.

1,270,679.

Specification of Letters Patent. Patented June 25, 1918.

Application filed June 25, 1917. Serial No. 176,854.

To all whom it may concern:

Be it known that I, CORNELIS ZULVER, a subject of the Queen of the Netherlands, residing at St. Helens Court, Great St. Helens, 5 in the city of London, England, have invented a new and useful Improvement in and Relating to Furnaces, of which the following is a specification.

This invention relates to furnace fronts 10 constructed with a fuel supply opening having around three sides thereof an air supply passage furnished with valves for controlling the admission of air, which air issues from the passage through a deflector 15 and flows into the furnace where it meets the fuel spray at approximately a right angle.

According to the present invention the air instead of directly issuing into the furnace 20 passes into the furnace front around the burner or burners and thence flows toward the fuel spray. The air supply is controlled by an upper valve which admits it into the air passage whence the air passes through 25 openings in the top and sides of the inner wall of the passage. Between the ends of the passage and the floor of the furnace front are two oppositely disposed openings closed by valves or doors. When burning 30 liquid fuel all the air inlets are opened and when burning solid fuel the openings in the sides of the air passage are closed in any suitable manner.

In the accompanying drawing—

35 Figure 1 is a view in longitudinal section of a boiler furnace provided with the improved construction of furnace front.

Fig. 2 is a plan view of the furnace front, and

40 Fig. 3 is a sectional view on the line $x-x$ in Fig. 1.

Fig. 4 is a sectional view similar to Fig. 3, but illustrating a modified construction.

The furnace front a is formed with a fuel 45 supply opening 1 around the upper portion of which is an air passage 2. The upper wall of said passage is formed with air-inlets 3 which are opened and closed by a slide 4 operated by means of a handle 5 from the 50 exterior of the furnace front. In the lower wall of the air passage and opposite to the air inlets 3 are openings 6 through which air enters the fuel opening 1. This lower wall of the air passage 2 is also formed with 55 two oppositely disposed openings 7, 7, which

are closed by doors, 8, 8, fastened by bolts 8^a. Below the closed ends of the air passage 2 are two more oppositely disposed openings 9, 9, formed in the wall of the fuel supply opening 1 and closed by pivotally 60 mounted doors 10, 10. These doors are opened and closed by means of levers 11, 11, respectively mounted at the extremities of spindles 12, 12, which extend through the door 13 of the fuel supply opening 1, and 65 which spindles are provided with handles 14, 14, on the outer side of the door 13. On each side of the fuel supply opening is a valve or damper 15 for controlling the supply of air to the underside of the fire-bars 16; 70 said dampers being opened and closed by means of handles 17, 17, on the outer side of the furnace-front. A handle 17 of the dampers 15 and the handle 5 of the slide 4 may be inter-connected, as shown on the one 75 side in Fig. 2, by links 5^a, 17^a, to a bell crank lever 19, so that the opening and closing of the slide and the dampers may be effected simultaneously. This insures a more suitable distribution and admission of 80 air into the fire-opening, thus promoting combustion. Moreover, the simultaneous closure of all the air valves prevents the admission of air when the burners are shut off, thereby avoiding damage to the boiler. 85 The links 5^a, 17^a, and the lever 19 may be either on the outside or the inside of the front plate.

The liquid fuel burner or burners 18 is or are mounted upon the door 13 of the fuel 90 supply opening, and when burning liquid fuel all the air inlets 3 and the openings 7 and 9 are opened to supply air for admixture with the fuel.

When it is desired to burn solid fuel the 95 door 13 with the burners thereon is removed and replaced by a fire-door of the usual type. The air inlet openings 7 and 9 are closed and the dampers 15 are opened.

Fig. 4 illustrates an alternative design in 100 which the air passage 2 around the fire-opening is continued to the floor of the furnace-front where additional air openings 20 are made. In this case, the air admission into the fire opening from the air passage 2 is 105 controlled by the slide 4, while the air through the floor of the furnace front is controlled by the valves 15, and the slide and the valves are connected together as previously described. When burning coal all 110

openings through the fire-door should be closed.

What I claim as my invention and desire to secure by Letters Patent, is:—

- 5 In combination with a furnace front having a fuel supply opening therein, spaced walls extending partly about said opening and forming an air space therebetween, both inner and outer walls having openings in the
- 10 upper parts of same, a slide valve controlling admission of air through the outer wall

openings, a handle on the exterior of the furnace for operating said slide, dampers for controlling the supply of air to the under sides of the furnace grates, handles for operating said dampers, a bell-crank lever, and links connecting said slide handle and a damper handle to be simultaneously operated from said bell-crank lever, substantially as described. 15

CORNELIS ZULVER.
